UNITED STATES PATENT OFFICE.

FRANK MATTUSCH, OF MUSCATINE, IOWA.

BLANK-CUTTER.

SPECIFICATION forming part of Letters Patent No. 553,493, dated January 21, 1896.

Original application filed March 26, 1895, Serial No. 543,275. Divided and this application filed October 12, 1895. Serial No. 565,465. (No model.)

To all whom it may concern:

Be it known that I, FRANK MATTUSCH, of Muscatine, in the county of Muscatine and State of Iowa, have invented certain new and useful Improvements in Blank-Cutters; and I do hereby declare that the following is a full, clear, and exact description thereof, reference being had to the accompanying drawings, and to the letters of reference marked thereon, which form part of this specification.

This invention is an improved machine for cutting blanks for buttons, &c., from shells, bone, &c.; and it consists in the novel construction and combination of parts hereinafter described.

This application for patent is a division of my application for patent on button-making machine, filed March 26, 1895, Serial No. 543,275, and the devices for trimming, polishing, and eyeleting the buttons are disclosed in said application and need no description herein. I do not, however, limit the present invention to its employment in connection with said machines.

The best form of the blank-cutter known to me is illustrated in the accompanying drawings, in which—

Figure 1 is a side elevation of the blank-cutter; Fig. 2, a vertical section through the same on line 2 2, Fig. 1. Fig. 3 is a detail.

Referring to the drawings, the device for cutting blanks from shells, &c., comprises an upright standard A having three lateral arms a a' a'', the lowest forming the base by which the standard is secured on the supporting-stand Z, while the two upper arms contain bearings for and guide a vertical shaft B, which can be lowered by means of a lever B' bearing on top of the shaft and connected by a rod B² with a treadle B³ below the table. The shaft is raised by a coiled spring b interposed between bracket a' and a collar b' on the shaft, as shown. On said shaft is a loose pulley C and fast pulley c, driven by a belt, (not shown,) which runs on pulley C when the shaft is raised and when the shaft is lowered is shifted onto pulley c by the shifter C', so that the shaft is rotated when it descends.

On the lower end of shaft B is a yoke E having a bottom cone E' and a hollow screw-

threaded shank E² below the cone. The cone fits in the bottom of a hollow casting F provided at one side with pairs of lugs F' embracing a guide-plate A² fastened to standard A, so that while the casting can move up and down it cannot rotate. The shank E² passes through an opening in the bottom of the casting, and the cutter-holder e³ is screwed thereon, thereby securing the casting to the shaft also. The cutter e is a hollow tube having serrations on its lower edge, and is adapted to cut round blanks from a shell, &c., laid on block A³ below the shaft, and as the blanks are cut successively each succeeding blank forces the preceding blanks farther up in the tube until they escape into casting F over the cone E', down which they slide to the sides of the casting, and wings E³ on the cone catch the blanks and carry them to the discharge-spout F² at the side of the casting through which they pass into a receiver. The blanks are then removed, and subsequently finished by other machinery or by hand.

Having thus described my invention, what I claim as new is—

1. In a blank cutter, the combination of the longitudinally movable rotatable shaft; the yoke and tubular cone attached thereto, and the hollow cutter attached to the cone in line with the opening therein, substantially as described.

2. In a blank cutter, the combination of the longitudinally movable rotatable shaft; the yoke and tubular cone attached thereto, and the hollow cutter attached to the cone in alignment with the opening therein; with means for rotating and reciprocating said shaft at the will of the operator, substantially as described.

3. The herein described blank cutter, consisting of the longitudinally movable rotatable shaft, the yoke and tubular cone attached thereto, the hollow cutter attached to the cone in line with the opening therein, and the non-rotatable hollow casting surrounding the cone, and means for rotating and reciprocating said shaft at will of the operator, substantially as described.

4. The combination in a blank cutter, of a rotatable yoke, a tubular cone attached to the

yoke, and the hollow cutter attached to the cone in alignment with the opening therein, substantially as and for the purpose described.

5 5. The combination in a blank cutter, of a rotatable yoke, a tubular cone attached to the yoke, and the hollow cutter attached to the cone in line with the opening therein, with the longitudinally movable rotatable shaft carrying the yoke, and the fixed hollow casting

surrounding the yoke and cone, substantially as and for the purpose set forth.

In testimony that I claim the foregoing as my own I affix my signature in presence of two witnesses.

FRANK MATTUSCH.
